UNITED STATES PATENT OFFICE.

ROY G. WASHER, OF MOHAWK, NEW YORK.

MOP WRINGER.

Application filed April 3, 1922. Serial No. 549,101.

To all whom it may concern:

Be it known that I, ROY G. WASHER, a citizen of the United States, and a resident of Mohawk, in the county of Herkimer and State of New York, have invented certain new and useful Improvements in Mop Wringers; and I do hereby declare that the following is a full, clear, and exact description thereof, which will enable others skilled in the art to which it appertains to make and use the same, reference being had to the accompanying drawings, and to the reference numerals marked thereon, which form part of this specification.

My present invention relates to mop wringers of the form where the mop is placed between two rollers which are rotated so as to move the mop lengthwise and at the same time pressed together so as to force the water from the mop.

The purpose of my invention is to provide a mop wringer of the type described which is simple, light in weight and very rigid and adapted to exert great pressure upon the mop with a minimum of power applied to the device.

A further purpose is to provide an article of the class described wherein the wringers are mounted on the ends of two pairs of pivoted arms projecting towards each other from a rigid rectangular frame at the top of the device and wherein great pressure may be obtained by toggle action particularly as the rolls are brought close together and almost in alignment with the pivoting points of the swinging arms.

Another purpose is to provide a mop wringer wherein rigidity is secured by improved form of construction, but with lightness of the parts and of the device as a whole; further to provide a device where a minimum of motion of the treadle produces a maximum of pressure upon the wringer rollers; further to so construct the device that friction is reduced to a minimum through having the moving points freely mounted whereby substantially all the power is exerted upon the mop and particularly results in being able to utilize a relatively light tensioned spring to move the wringer rolls to open position.

Further objects are to provide a mop wringer of such form, construction and combination of its parts as to form a device that can be easily and conveniently operated, which is not apt to get out of order,

but which can be readily repaired or have parts thereof replaced.

Further purposes and advantages of my invention will appear from the specification and claims herein.

Fig. 1 is a perspective view of a mop wringer embodying my invention with the wringer rollers brought towards each other and engaging a mop.

Fig. 2 is a side elevation of the wringer as seen from the left side.

Fig. 3 is a top or plan view with the right hand ends of both rollers in longitudinal section.

Fig. 4 is a vertical sectional view of one-half of the machine on line 4-4 of Fig. 2.

Fig. 5 is a horizontal sectional view of one side of the device on line 5-5 of Fig. 2 on an enlarged scale.

Fig. 6 is a vertical sectional view on a similarly enlarged scale on line 6-6 of Fig. 2.

Referring to the drawings in a more particular description it will be seen that the mop wringer comprises a platform 10 from the opposite sides of which rise rigid side frames the tops of which are provided with side top pieces 11 the ends of which are connected by front and rear top pieces 12 and 13 forming a rigid rectangular frame at the top of the device within which frame are swingingly mounted the front and rear wringer rolls 14 and 15.

The side frames of the device are composed of a long bar 16, a short bar 17 and an intermediate lengthed bar 18. The long bar 16 has its lower end secured to the platform near its rear corner as by screw 19 while the said rod extends upwardly and forwardly in a slanting direction and has its upper end secured to the side top piece 11 near its forward end rigidly by the headed screw 20 and nut 21. The short bar 17 has its lower end secured as by screw 22 to the side or edge of the platform near its forward corner while the upper end of said bar is rigidly connected to the lower end of the bar 18 as by bolt 23 and nut 24 at a point substantially directly above the lower end of bar 17. The bar 18 extends upwardly and rearwardly and is rigidly secured at its upper end to the side top piece 11 near its rear side as by headed screw 25 and nut 26. Where the bars 16 and 18 cross they are rigidly connected as by bolt 27.

It will now be seen that each side frame

including as it does a side top piece 11 is a very rigid construction. The front and rear top pieces 12 and 13 have their opposite ends rigidly secured to the ends of the 5 side top pieces 11 as by headed screws 27. It will be noted that the top rectangular frame composed of the side top pieces 11 and the front and rear pieces 12 and 13 form a rigid frame well adapted to mount 10 the wringer rollers as hereinafter described without placing any appreciable strain upon the bars of the side frames. The headed screws 20 and 25 not only connect the upper end of the bars 16 and 18 to the side top 15 piece 11 as already described but afford the means of pivotally mounting the swinging arms 28. The said headed screws 20 and 25 have their heads on the inside of the top rectangular frame and spaced along on the 20 shank of the said screw a short distance from its head is a shoulder 29 taking against the inner surface of the side top piece 11 and allowing the swinging arms 28 to be mounted on the shank of the headed screw 25 as a pivot, but without pressure or binding strain upon the said swinging arms. The arms 28 are mounted in pairs on each side of the machine, each of the rear arms having a hole near its free end forming a bearing in which is mounted the stub shaft or pin 30 projecting from the opposite ends of the rear wringer roller 15. In a similar way the two forward swinging arms 28 support the stub shaft or pin 31 of the front 35 wringer roll 14.

Loosely mounted upon the said pins of the wringer rollers and inside of the swinging arms 28 are the upper ends of the forward and rearward connecting rods 32 and 40 33 respectively. The lower ends of the connecting rods on either side of the machine are brought together and pivotally connected as by bolts 34 to the legs of the U-shaped treadle 35. The forward end of 45 the legs of this treadle are pivoted to the forward part of the side frames as by being mounted upon the bolts 23 on the inner side of the frame said bolts being provided with shoulders or other means to keep the head 50 of the bolt from pressing against the treadle. Similarly the bolt 34 has a shoulder or other means spaced from its head so as to allow the lower ends of the connecting rods 32 and 33 to freely swing on said bolt.

55 On the outer part of the bolt 34 is provided a holder 36 like a grooved pulley and a similar holder 37 is provided on the outer end of the bolt 27. Mounted upon these holders and stretched between the holders 60 on each side of the machine there is provided an endless coiled spring 38 of such strength as to hold the rollers and treadle and attached parts in upper or inoperative position when no power is applied to the 65 machine. The swinging arms 28 are of

such length and the parts are so proportioned that as the foot is placed upon the rearwardly extending peddle portion 39 of the treadle 35 the upper ends of the connecting rods 32 and 33 will draw the 70 wringer rollers down and towards each other on their swinging arms 28 forming as will be seen from Fig. 1 a sort of toggle action which will bring the rollers with 75 increasingly greater pressure against the mop as the rollers approach their lower position. As all the moving parts are relatively light and swing freely on good bearings very little tension from the spring 38 is required to return the rollers to upper or 80 inoperative position when the foot is removed from the peddle. It follows from this that while the spring is placed under tension during the downward or working stroke of the treadle the slight power used 85 therefor is not noticeable and is a great saving in labor over the mop wringers requiring greater tension for return of the parts to expanded position.

Upon the projecting pin preferably of 90 the forward roller there is mounted a crank 41 with handle 40 whereby in an obvious manner the forward roller may be rotated. Preferably this forward roller is corrugated 95 so that as the said roller is rotated clockwise as seen from the right-hand or handle end the mop will be positively grasped and forced upward in the desired manner. It will be understood of course that in this style of wringers the upper part of the wet 100 mop is placed between the wringer rollers and the mop moved upwardly forcing the water continually further down on the mop and allowing the water to fall into the pail (not shown) upon the platform beneath the 105 wringer rollers.

The heads of the screws 20 and 25 form 110 inwardly extending stops to engage the connecting rods 32 and 33 respectively as the rollers come to separated position thus forming a positive stop at the upward movement of the rollers and preventing their accidentally going past center relative to the force communicated to the rollers from the said connecting rods.

115 It will be noted that when the wringer rollers are forced downward and the greatest pressure exerted thereby the strain of such pressure is communicated back as a thrust through the short swinging arms 28 120 and then taken as a direct pulling strain upon the opposite ends of the top side pieces 11 thus operating to relieve the members of the upright side frames from any appreciable strain from such pressure.

125 What I claim as new and desire to secure by Letters Patent is:

1. In a mop wringer the combination of a platform, rigid side frames extending upward from two opposite sides thereof, front 130

and rear pieces connecting the top corners of the opposite side frames, front and rear wringer rollers, a crank handle connected to one of said rollers, arms pivoted at each corner of the top of the frame arranged in front and rear pairs with the rollers journaled in the free ends and adapted to have the rollers swing downwardly towards each other and upwardly away from each other, a U-shaped treadle having its ends pivoted to the forward part of the side frames and with its foot piece extending to the rear of the frame, two connecting rods at each side of the frame pivoted to the arms of the treadle below the rollers and with their upper ends operatively connected to the free ends of the swinging arms and a spring adapted to raise the rollers to open position.

2. In a mop wringer the combination of a platform, rigid side frames extending upward from two opposite sides thereof, front and rear pieces connecting the top corners

of the opposite side frames, front and rear wringer rollers having pivot pins projecting from their opposite ends, a crank handle on one of said pins, arms pivoted at each corner of the top of the frame arranged in front and rear pairs with the roller pins journaled in the free ends and adapted to have the rollers swing downwardly towards each other and upwardly away from each other, a U-shaped treadle having its ends pivoted to the forward part of the side frames and with its foot piece extending to the rear of the frame, two connecting rods at each side of the frame pivoted on a common axis to the arms of the treadle below the rollers and with their upper ends mounted upon the pins of the front and rear rollers and a spring adapted to raise the rollers to open position.

In witness whereof I have affixed my signature, this 25 day of February, 1922.

ROY G. WASHER.
